GASEOUS ELECTRIC DISCHARGE LAMP
DEVICE

Karl Weidhaas, Berlin-Treptow, Germany, assignor to General Electric Company, a corporation of New York

Application January 9, 1934, Serial No. 705,937
In Germany January 12, 1933

4 Claims. (Cl. 176—1)

The present invention relates to gaseous electric discharge lamp devices and more particularly the invention relates to lamp units incorporating such devices wherein the series resistance for the discharge device is in the form of an incandescent filament and is a light emitting element.

When the container of the electric discharge device and the incandescent filament are mounted in a common envelope provided with a screw-base a lamp unit emitting mixed light from both the incandescent filament and the gaseous electric discharge is made available for illuminating purposes or the like. I have observed that when the discharge device has a tubular container and the envelope an elongated bulb shape the lamp unit frequently fails when the longitudinal axis of the container is located in the longitudinal axis of the envelope or at right angles thereto.

The object of the present invention is to provide a lamp unit of the above type having a long useful operating life. Another object of the invention is to provide such a lamp unit wherein the emitted light is utilized to the best advantage for illuminating purposes. Still further objects and advantages attaching to the device and to its use and operation will be apparent to those skilled in the art from the following particular description.

The invention attains its objects by mounting the container of the discharge device at an acute angle with respect to the longitudinal axis of the envelope enclosing said container. The series connected incandescent filament is mounted in a plane substantially at right angles to the longitudinal axis of the container of the discharge device. I have found by actual use that the life of a lamp unit has a longer operating life and a better light distribution than similar lamp units wherein the longitudinal axis of the container is coincident with the longitudinal axis of the envelope or at right angles thereto.

In the drawing accompanying and forming part of this specification an embodiment of the invention is shown in a front elevational partly sectional view, but as such illustration is primarily for purposes of disclosure it will be understood, of course, that numerous changes in the form and details of the device and in its use and operation may be made by those skilled in the art without departure from the spirit and scope of the invention.

Referring to the drawing the new and novel lamp unit comprises a gaseous electric discharge device having a tubular container 2 mounted in

an envelope 1. Said envelope 1 is tubular in shape and the end thereof is enlarged and substantially spherical in shape. Said container 2 is supported in said envelope 1 by support wires 5 and 6 sealed into the pinch-part 3 of the stem 4 of said envelope 1. Said envelope 1 is provided with a screw-base 9 of conventional design having a contact button 8 insulated from the shell of said base 9 which shell is another contact. Said support 5 is connected to contact 8 by lead 7, indicated in dotted lines in the drawing, and to the current lead of the electrode 10. Said support 6 is connected to the current lead of the electrode 11. Said electrodes 10 and 11 consist of a coiled metal wire, such as a tungsten or nickel filament, coated or impregnated with an electron emitting material, such as barium oxide, and are electron emitting when heated. Two perforated metal discs 12 and 13 are adjacent and interposed between the electrodes 10 and 11 respectively. Said discs 12 and 13 are supported by wires 14 and 15 sealed into the ends of said container 2. Said wire 15 is connected to the current lead 7 through resistance 16. A support wire 17 for the filament 19 is sealed into the pinch part 3 of said stem 4 and said wire 17 is connected by lead 18 to the contact shell of the base 9. The filament 19 consists of a coiled tungsten wire and is heated to incandescence during the operation of the gaseous electric discharge device. Said filament 19 is likewise supported by the support 6 and the wires 20 fused into a glass bead fused to the leads for said electrode 11 and said disc 13. Said filament 19 is circular in shape and is mounted about said container 2 in a plane substantially at right angles to the longitudinal axis of said container 2. The longitudinal axis of said container 2 is at an acute angle to the longitudinal axis of said envelope 1.

The container 2 has a gaseous filling therein comprising a starting gas, such as neon or argon, and a vaporizable material such as mercury, cadmium, or one of the alkali metals, such as sodium. The envelope 1 is either evacuated or filled with an inert gas having poor heat conductivity characteristics in accordance with the well known incandescent lamp practice. The envelope 1 is a heat conservator for said container 2 and said container 2 is at an elevated temperature during the operating period of the lamp unit. The vaporizable material is thus at an effective vapor pressure during this period. The high current density in the discharge path, made possible by the use of electron emitting

electrodes 10 and 11, also aids in maintaining said container 2 at an elevated temperature.

When potential is applied to the above described lamp unit current flows first through the 5 current supply lead 18, support wire 17, the filament 19, support wire 6, electrode 11, auxiliary electrode 13, the lead 15, the resistance 16 to the other current supply lead 7. As soon as the discharge path between the main discharge sup- 10 porting electrodes has been sufficiently ionized by the auxiliary discharge between said electrodes 12 and 13, the main discharge starts in the device and current then flows through the filament 19, the lead 6, the electrode 11, the electrode 10, the 15 lead 5, the lead 7 and to the contact 8 of the socket 9. The auxiliary discharge is thus in parallel with the main discharge and ceases entirely or is very weak during the operation of the lamp device due to resistance 16. The heat of the main 20 discharge in the gas vaporizes the vaporizable material in said container 2 which vapor then participates in the discharge. The light emitted by the lamp unit is a mixture of the light emitted by the incandescent filament 19 and the gaseous 25 electric discharge device.

A lamp unit having the above described structure has a long, useful operating life and the light emitted thereby is utilized to better advantage than in prior devices of this type. When desired 30 the container 2 and the envelope 1 are made of a material which transmits ultra-violet radiations, such as quartz. While I have shown the container 2 as being in a plane passing through the pinch part 3 of the stem 4 it will be understood of course 35 that said container 2 can be out of this plane, when desired.

What I claim as new and desire to secure by Letters Patent of the United States is:—

1. A lamp unit comprising in combination an 40 envelope, an incandescent filament and a gaseous electric discharge lamp device mounted in said envelope, said lamp device comprising a straight, sealed, tubular container having electrodes mounted axially therein adjacent each end there- 45 of and having a gaseous atmosphere therein, the longitudinal axis of said container being at an acute angle with respect to the longitudinal axis of said envelope, said filament being mounted in a plane substantially at right angles to the longi- 50 tudinal axis of said discharge device, said dis-

charge device and said incandescent filament being connected in series.

2. A lamp unit comprising in combination an envelope, an incandescent filament and a gaseous electric discharge lamp device mounted in said 5 envelope, said lamp device comprising a straight, sealed, tubular container having electrodes mounted axially therein adjacent each end thereof and having a gaseous atmosphere therein, the longitudinal axis of said container being at an acute angle with respect to the longitudinal axis of said envelope, said filament being mounted in a plane substantially at right angles to the longitudinal axis of said discharge device and being located between the ends of said discharge device, 15 said discharge device and said incandescent filament being connected in series.

3. A lamp unit comprising in combination a sealed envelope, a gaseous filling therein and a gaseous electric discharge lamp device mounted 20 in said envelope, said lamp device being completely enclosed by said envelope and comprising a straight, sealed, tubular container of vitreous material having an axially protruding seal at each end thereof, solid, thermionic electrodes 25 mounted axially therein adjacent each end thereof, an annular member interposed between said electrodes and axially mounted in said container to guide a constricted arc discharge away from the walls of said container and a gaseous atmosphere in said container, the longitudinal axis of said container being at an acute angle with respect to the longitudinal axis of said envelope to facilitate cooling of said seals by convection currents during the operation of the device. 35

4. A lamp unit comprising in combination a sealed envelope, a gaseous filling therein and a gaseous electric discharge device mounted in said envelope, said lamp device being completely enclosed by said envelope and comprising a straight, 40 sealed, tubular container of vitreous material having an axially protruding seal at each end thereof, solid thermionic electrodes mounted axially therein adjacent each end thereof and having a gaseous atmosphere therein, the longitudinal axis of said container being at an acute angle with respect to the longitudinal axis of said envelope to facilitate cooling of said seals by convection currents during the operation of the device. 45
